BIAGIO MARTINI, OF PITTSBURGH, PENNSYLVANIA

RAILROAD TRACK-SWITCH

Application filed July 20, 1931. Serial No. 551,822.

This invention relates to railway track-switches.

One of the primary objects of this invention is to provide a track-switch which prevents derailments of railroad cars or engines when the latter are moved backward from a branch line onto the main line. Another object is to provide such a switch whereby, regardless of the position in which said switch is set, cars or engines moved backward from a branch track will always be led onto the main track, thus obviating the need of a switch man leaving the train on such backward shifting of cars or engines to properly set the switch. A further object is to provide a switch of this character which cannot be easily clogged up by ballast stones and whereby the latter will be automatically pushed out of the switch during the operation thereof. Still another object of this invention is to provide a railroad track switch which is very compact and self contained, which is well adapted for rugged construction, and which can be easily operated either manually or by power means.

Additional features and advantages of this invention will appear in the following description considered in connection with the accompanying drawings forming part of this application.

In the drawings:

Fig. 1 is a top plan view of a so called left hand switch built in accordance with my invention, this figure also showing one of many available constructions for the manual operation of the switch.

Fig. 2 is a similar view to Fig. 1, but showing the switch shifted into its other operative position.

Fig. 3 is a top plan view of the base plate of the switch.

Fig. 4 is a cross-sectional view through the base-plate of the switch, taken on line 4—4, Fig. 3.

Fig. 5 is a top plan view of the frame of the switch.

Fig. 6 is a side elevation, partly in section, along line 6—6, Fig. 5 of said frame.

Fig. 7 is another side elevation of the frame.

Fig. 8 is a side elevation of the manual operating mechanism for the switch, in the position corresponding to Fig. 2. 55

Fig. 9 is a top plan view of the complete spider of the switch.

Fig. 10 is a side elevation of the spider-block.

Fig. 11 is a top plan view of said spider 60 block.

Fig. 12 is a bottom plan view of the spider block.

Fig. 13 is a top plan view of the tongue member of the spider. 65

Fig. 14 is a side elevation of said tongue-member and

Fig. 15 is a bottom view thereof.

Fig. 16 is a top plan view of the spider for the so-called right hand switch. 70

Fig. 17 is a plan view showing switches of my invention applied to a portion of a railroad track.

The two switches required for each branch line are referred to as the right hand and the left hand switches according to their position relative to the direction of approach from the main line toward the point of ramification. Thus, in Fig. 17, wherein the upper, single track, portion is assumed to be part of the main track, the switch nearest the operating mechanism is called the left hand switch, and the other, the right hand switch. 75

Each switch consists of the following main parts: a frame 1, an oscillatable spider 2 and a switch-base 3. 80

The frame member comprises a circular crown 4 provided with the four symmetricaly disposed feet 5 by means of which the crown is supported the desired distance above the base-plate and secured thereon by means of bolts 6. 85

Secured to the crown 4 are the substantially radially disposed lugs 7 and 8, the former serving for the securement to the switch of the end of one of the main-track rails, while the latter acts as the clamping and spacing block for one main track-rail and one branch-rail. Suitable clamping bolts 9 are shown for fastening the rails to the switch. 90

Fig. 6 is a side elevation, partly in section, along line 6—6, Fig. 5 of said frame. 100

A bracket 10 is also secured to the top of the crown, as shown, said bracket serving as a support for the vertical shaft of one of the levers of the switch operating mechanism, as will be explained hereafter.

5 The spider comprises a spider-block 11 and a tongue 12 the latter being held on the block in yielding contact relation by means of the stud-bolts 13 and the springs 14. The block is oscillatably mounted on the base by means of a pivot-pin 15 engaging a bearing 16 positioned in the base-plate.

10 Upon said base-plate are provided the arcuate pads 17 and 18, having finished top surfaces to act as supports for the ends of the oscillating spider. The pad 17 is made considerably wider than the pad 18 to afford an ample support for the pointed end of the spider tongue.

15 The spider-block comprises a massive body portion 19 the top of which is level with the top of the track-rails, and in which are provided the converging grooves 20 and 21 of sufficient depth and width to accommodate the flanges of the wheels of the engines and cars. A portion is cut away from the top of the block to form a recess 22 which accommodates the spider-tongue and whereby there is produced in the block an island 23 in which is cut the prolongation of the flange-groove 20. At the base of both ends of the spider-block there are provided the arcuate flanges 24, 25, finished at the top and bottom and adapted to slidably bear on the base-pads 17, 18 and the lower edges 26 of the crown 4. The purpose of these flanges is to prevent any tilting or rocking movement of the spider, especially in a longitudinal direction, when engaged by the engine or the car-wheels.

20 The spider-tongue consists of a rectangular prismatical body portion 27 terminating with a wedge portion 28. The top of the spider is, of course, level with the spider-block and has cut therein the flange-grooves 20^a, 21^a complementary of the grooves 20, 21. On the underside of the tongue there is provided, on the bias, a recess 29 adapted to be engaged by the reduced portion produced on the block by the recess 22. The holes 30, adjacent both ends of the tongue are intended for the stud-bolts 13, and spacer rings 31, 32 are used to hold the tongue in proper spaced relation to the spider-block. The body portion 27 of the tongue has also a flange 25^a which forms the continuation of the flange 25.

25 As stated, the right and left hand track-switches may be operated simultaneously either manually or by means of power driven contrivances, of standard construction used in railroad work. The manually operated mechanisms shown in the drawings consists of an operating-lever 33 hingedly mounted at 34, on a vertical support 35 secured on the base 36 fastened by screws 37 to two adjacent rail-ties 38. To the lever 33 is hingedly con-

nected one end of the connecting-rod 39 the other end of which is hinged to a lever 40 secured at the top of a shaft 41 rotatably supported in the base 36 and a stirrup 42 secured on the underside of said base. Secured on shaft 41 and within the bight of this stirrup is a lever 43 to which is hingedly connected the connecting-rod 44 hinged at the other end to the lever 45 secured at the lower end of the vertical shaft 46 rotatably mounted in the bracket 10 of the crown and in a suitable bearing 47 provided in the switch-base 3. Intermediate the latter and said bracket 10 is keyed on the shaft 46 the bell-crank lever 48 to which are hinged the two links 49, arranged in overlapping crossed relation, and hingedly connected to the lugs 50 provided at one side of the spider-block 11.

30 The right and left hand switches are connected together for simultaneous operation by means of a connecting-rod 51, Fig. 17, hinged to the levers 45 of both track-switches. The angular movement of the spider, in both directions, is limited by means of stops 52 provided on the inner face of the crown 4. On the top of the latter are also cut in proper relation to the rail-heads the grooves 53, 54 and 55 to accommodate the wheel-flanges.

35 The two operative positions for the spider of the left hand switch obtained by the manipulation of the operating lever 33 are shown in Figs. 1 and 2.

40 Referring in particular to Figs. 1, 2 and 17 in which the track wheels 56 are suggested in dot and dash lines, the operation of my safety switch may now be succinctly described, it being supposed that the rail sets 57 and 58 form respectively the main and the branch track.

45 Assuming for instance that a train on the upper section of the main track 57 (Fig. 17) must be transferred to the branch track 58, the left hand switch would be placed in the position shown in Fig. 1, that is, the wheel flanges would engage the crown-slot 54, follow along the left hand side of the spider-tongue 12, pass the crown-groove 53 and the wheels would finally travel on the tracks 58. If on the other hand the train is to continue traveling on the main track 57, the left hand switch would be set as shown in Fig. 2, in which case the wheel-flanges would successively engage the crown-groove 54, the spider-groove 20, 20^a, 20 and the crown-groove 55 before the wheel would travel on the lower section of the main track.

50 Similarly, if a train should have to be moved from the branch track 58 onto the upper section of the main track 57, the left hand switch should again be shifted into position shown in Fig. 1, as will be readily understood. However, if by error said switch should be set as per Fig. 2, it will be noted that the wheel-flanges would engage successively the crown-groove 53, the grooves 21,

21^a, follow the left hand side of the so-called island 23 of the spider-block, enter the crown-groove 54, after which the track wheel would ride on the upper section of the main track. With the old type track-switches, such erroneous setting would cause a derailment, if not corrected in time.

If a train is to be moved from the lower section of the main track onto the upper section, the left hand switch should be in the position represented in Fig. 2. If instead it happens to be set as in Fig. 1, the transfer will still be made safely, i. e. without derailment, because in this case the wheel-flanges will engage consecutively the crown-groove 55, the wedge-shaped space 59 between the spider-block and spider-tongue defined by the spacer-rings 31, 32, and the crown-groove 54 prior to the wheels engaging the rails of the upper section of the main track. In this case, the wheel flanges, overcoming the resistance of the springs 14, will temporarily force the spider-tongue away from the spider-block, and allow the faces of the wheels to ride over the top of the spider-body. The recess 22 is wide enough to freely accommodate the spider-tongue and a wheel-flange.

It is of course understood that the same safety features apply to the right hand switch in which, as suggested in Fig. 17, the spider-block and tongue are mounted in reversed relation to the left switch.

Because the transferring of whole trains or individual cars from the branch track or the lower main track section on the upper section of said main track is always possible, regardless of the setting of the track-switches, no attendant need be employed to manipulate said switches and considerable time may be saved.

Referring to various figures of the drawings, it will be noted that the pointed end 60 of the spider-tongue does not reach quite to the end of the spider-block; this is done to enable the faces of the track-wheels to come onto the top of the spider-block before engaging the relatively weaker tongue-point.

An important feature in the construction of my switch lies in placing the crown a substantial distance above the switch-base, to render said switch practically self-cleaning. It will be noted that stones,— of the size used as ballast,— falling between the spider-member and the crown will be gradually forced out of the switch by the oscillating movements of said spider member, through slot-openings defined by the lower edges 61 of the crown and the base-plate. Smaller stones will also be forced out, in the same manner, through the narrower slots provided for the guidance of the spider-flanges 24, 25. Similar stones falling between the switch-points and the stationary rails of an ordinary switch, as now used generally in railroad

work would prevent the closing of said switch and might be the cause of a derailment.

As will be understood, there may be changes made in the construction and arrangement of the details of my invention without departing from the field and scope of the same, and I intend to include all such variations, as fall within the scope of the appended claims, in this application in which the preferred form only of my invention is disclosed.

I claim:

1. In a railroad track-switch of the character described, a base; a cylindrical crown supported thereon in spaced parallel relation; a spider-member comprising a spider-block and a separate spider-tongue partly supported by the block; yielding means to hold said tongue in cooperative relation to said block; a pivot-pin positioned on the spider-block and rotatably supported on the base, and means to oscillate said spider-member within the crown.

2. In a railroad track-switch of the character described, a horizontal base; a cylindrical crown supported thereon in spaced parallel relation; a spider-member comprising a spider-block and a separate spider-tongue partly supported by the block; yielding means to hold said tongue in cooperative relation to said block; a pivot-pin positioned on the spider-block and rotatably supported on said base; means positioned on the base for slidably supporting the ends of said spider-block and tongue; means to oscillate said spider-member within the crown, and means to limit the oscillatory movements of the spider-member.

3. In a railroad track-switch of the character described, a horizontal base; a cylindrical crown supported thereon in spaced parallel relation; a spider-member comprising a spider-block and a separate spider-tongue having interengaging recesses wherat the tongue is partly supported by the block; yielding means to hold said tongue in cooperative relation to said block; a pivot-pin positioned on the spider-block and rotatably supported in said base; means to oscillate said spider-member within the crown, and rigid means to limit the oscillatory movements of the spider-member.

4. In a parallel track-switch of the character described, a horizontal base; a cylindrical crown supported thereon in spaced parallel relation; a spider-member oscillatable within the crown and comprising a spider-block and a separate spider-tongue partly supported by the block; yielding means to hold said tongue in cooperative relation to said block; means positioned on the crown for securing thereto one rail of the main track; unitary means for securing one rail each of the converging main and branch-tracks; said spider-block and spider-tongue

having converging and co-axially disposed grooves engagable by the flanges of track-wheels and adapted to be set in cooperative relation with said main track rails and the branch-rail, and means to oscillate the spider-member.

5. In a railroad track-switch of the character described, a base; a cylindrical crown supported thereon; a spider-member oscillatably mounted within the crown and comprising a spider-block and a separate spider-tongue movably mounted on said block; means to secure said tongue against longitudinal movement; transversely effective means to yieldingly hold the tongue against said block in cooperative relation therewith, and means to oscillate said spider-member.

6. In a railroad track-switch of the character described, a horizontal base; a cylindrical crown supported thereon; a spider-member oscillatably mounted within the crown and comprising a spider-block and a separate spider-tongue movably mounted on said block; means to secure said tongue on said block against longitudinal movement; transversely effective means to yieldingly hold the tongue against said block in cooperative relation therewith; means positioned on the base for slidably supporting the ends of said spider-block and tongue; means to oscillate said spider-member and means to limit the oscillatory movement thereof.

In testimony whereof I affix my signature.
BIAGIO MARTINI.
